UNITED STATES PATENT OFFICE.

JACQUES COUTURIER, OF LYONS, FRANCE.

WEATHER-STRIP.

SPECIFICATION forming part of Letters Patent No. 300,849, dated June 24, 1884.

Application filed August 20, 1883. (No model.) Patented in France February 16, 1883, No. 153,854.

To all whom it may concern:

Be it known that I, JACQUES COUTURIER, of Lyons, in the Republic of France, have invented an Improvement in Weather-Strips, of 5 which the following is a specification.

My invention, although primarily intended as a weather-strip for doors and windows of all kinds, may be applied to trunks, boxes, and other articles having covers, to close as 10 far as possible any space that may exist between the cover and the body of the trunk or box, and thereby prevent the admission of air, dust, or moisture to the interior of the box or other article to which the device is applied.

15 My improved weather-strip consists of a strip of metal of the desired length, on one side of which felt, leather, india-rubber, cork, cloth, or other elastic material is secured, and this metal strip is within a case that has an 20 opening in its face extending its entire length, so that the elastic material can pass through said opening and project beyond the face of the case. There are springs between the metal plate and the inside of the case that press 25 forward the metal plate carrying the elastic material, and flanges formed by the metal at the edges of the opening retain the plate in the case. The case is to be let into the wood of 30 the door or cover or into the stop-bead or jamb of the door-frame, or into the top edge of the body of the trunk or box, or placed upon either of these. In either case, when the door or cover is closed, the elastic material is pressed by the springs tightly against the part 35 it comes into contact with and closes quite effectively any opening that might otherwise exist at such place, and the weather-strip, composed of the plate, the elastic strip, and the springs within the case, is complete in itself 40 and adapted to be sold independently of the article to which the same may be fastened.

In the drawings, Figure 1 is a longitudinal section of a piece of my improved weather-strip. Fig. 2 is a cross-section of the same. 45 Fig. 3 is a horizontal section showing the weather-strip let into the door-frame. Fig. 4 is a similar view showing the weather-strip supported upon the face of the door-frame. Fig. 5 is a horizontal section showing the improvement applied to a double door. Fig. 6 50 represents the weather-strip applied to the

lower part of a door, the parts being in the position they assume when the door is open. Fig. 7 is a sectional plan of some of the parts shown in Fig. 6; and Fig. 8 shows the same 55 parts as in Fig. 6, but the door is represented as closed.

A represents a sheet-metal case or box that has sides, back, and front, and may have ends, and it is to be of a length to adapt it to the 60 place to which the weather-strip is to be applied. There is an opening extending the entire length of the front of the case, and the metal at the edges of this opening forms flanges a a, which retain the strip of metal B 65 within the case. The strip of metal B is about the same length as the case A, and to the front of this strip is secured the elastic material C, which is of a sufficient thickness to pass through the opening in the case and project beyond the 70 face of the case when the plate B is pressed forward by the springs D, that are between the plate B and the interior of the case A. There may be two or more of the curved springs D secured to the case A, as in Fig. 1; or one 75 long spring of undulating form may be used for pressing forward the plate B and its elastic strip C.

In Fig. 3 I have shown two of the weather-strips applied to the door-frame, each case A 80 being in a groove made in said frame and with the face of the case flush with said frame. In Fig. 4 the case A is supported by angle-irons l upon the surface of the door-frame. In this instance it is necessary to apply a strip of 85 wood or other material at m to come against the elastic material C when the door is closed.

In order to apply this weather-strip to the bottom of doors, I add to the parts before described a plate, E, that is free to slide in the 90 case A. One end of each spring D is secured to the plate E, and the other end comes against a stop, D, upon the case A. The outer end of the plate E is inclined at b, and there is an incline at 2 upon the door-frame; hence when the door is closed and the incline b comes against 2 the plate E is forced along endwise, which bends the springs to a smaller curve, and causes the springs to press the weather-strip tightly against the sill of the door. When 95 the door is opened and the inclines b and 2 separated, the springs D straighten out, move

the plate E, and lift the strip up, so that said strip offers no obstruction to the free opening or closing of the door. I prefer to make the plate B, Figs. 6, 7, and 8, U-shaped to receive 5 the strip of elastic material C.

I am aware that previous to my invention weather-strips had been made of a plate having a strip of elastic material upon one face, and with springs at the rear of the plate to 10 press forward the plate and strip; and I am also aware that such a weather-strip has been let into a recess or mortise in the door and has been retained in place by plates applied at the edges of the recess.

15 I am further aware that a spring has been employed to lift the weather-strip from the door-sill when the door is open, and also that a sliding bolt has been used to force the weather-strip to the sill when the door is closed.

I claim as my invention—

The case A, having sides and back and a front with an opening in it, in combination with the plate B, that is retained within the case by the front plate of the case, an elastic strip, C, upon the outer face of the plate B 20 and projecting through the opening in the front of the case, and a spring or springs, D, between the plate B and case, substantially as set forth.

The foregoing specification of my improvement in weather-strips signed by me this 10th day of July, 1883. 30

JACQUES COUTURIER.
